KITE APPARATUS

John Sylvester Wheelwright, Tonbridge, England

Application October 5, 1942, Serial No. 460,793
In Great Britain April 30, 1942

13 Claims. (Cl. 244—153)

This invention relates to kite-apparatus for projecting and maintaining lines or cables, as in the provision of radio aerials for aircraft dinghies, ships' lifeboats, life-saving rafts and the like, or in the raising of a lethal cable barrage for defense against aircraft on land or at sea.

The invention has for its main object to provide an improved construction of kite adapted for compact folding to a shape suitable for projection and for automatic unfolding to its flying form when it reaches the limit of extension of the line or cable by which it is to be flown.

Another object of the invention is to provide a cover or container in which the folded kite is enclosed for projection, the cover being held around the kite by fasteners which are released automatically by the line or cable when extended.

A further object of the invention is to provide a kite-cover or container having a required length of line or cable stowed therein in such a manner as to be capable of being drawn off without fouling or entanglement while the cover enclosing the folded kite is being projected to the desired height.

Other objects and advantages of the invention will appear hereinafter from the following description of a preferred embodiment, reference being made to the accompanying drawings, in which:

Fig. 1 is an elevation of the kite in open condition.

Fig. 2 is a perspective view of the kite in flying form.

Fig. 3 is an elevation of the kite partly folded.

Fig. 4 shows the kite enclosed.

Fig. 5 is an elevation of the cover in open condition.

Fig. 6 shows the cover closed and a rocket connected to the kite enclosed in the cover.

Fig. 7 illustrates the use of the apparatus for projecting a kite from an aircraft dinghy.

Figs. 8 to 12 illustrate details of construction as hereinafter described.

Referring to Figs. 1 and 2, the kite illustrated is of well-known type comprising a substantially flat main sail *a* carried by parallel booms *b*, from the end portions of which a pair of angularly disposed jib sails *c* extend to a third boom *b*¹ fitted with flying bridles *d* to which the upper end of the line *e* is attached by a runner *d*¹. According to my invention, the kite is provided with a hinged frame having its joints controlled by spring devices in such a way that the kite can be folded compactly for projection to a required height; for this purpose, the kite is fitted with

a transverse spar made in two sections *ff*¹ which are normally extended in line and partly overlapping so as to maintain the booms *b* spaced apart and the main sail *a* in taut condition. The two spar sections are jointed together centrally of the kite by means of a transverse hinge-pin *f*², as shown in Fig. 8, a rubber ring *f*³ being fitted around the joint, if desired; their outer or remote ends are engaged in pockets *a*¹ at opposite corners of the main sail, and their inner or adjacent ends are fitted, as shown in Fig. 9, with forks *f*⁴ pivotally engaged upon slides *b*² movable along the booms *b*, which as well as the members *ff*¹ are preferably made of light metal tubing. Springs in the form of bunches of elastic rubber threads *g* are connected between suitable points *f*⁵ on the respective members *ff*¹ and the upper ends of the booms *b*, the tension of these springs urging the members into line so as to overlap between the booms *b*; by shifting the slides *b*² downwards along the booms, the members *ff*¹ can be brought to crossed relation, as seen in Fig. 3, against the tension of the springs *g*, the booms being at the same time caused to approach until in the closed condition shown in Fig. 4 all the booms *bbb*¹ and both spar-sections *ff*¹ are substantially parallel and the sails *ac* can be folded compactly together for enclosure in a cover or container.

30 The cover *h*, shown in Figs. 5 and 6, is formed of flexible material such as fabric, capable of being wrapped around the folded kite; two or more thicknesses of fabric are employed, these being seamed together longitudinally by parallel rows of stitching *h*¹ so as to provide a plurality of long and narrow cells *h*² in one or more layers, for example in two layers, as shown in Fig. 10. The number of thicknesses of fabric employed, and consequently the number of layers of cells 35 between such thicknesses, as well as the number of cells in the layer or in each layer, will depend upon the size of kite and the length of line to be packed. Into these pockets the line *e* is carefully drawn so as to form a series of 40 separate loops extending for substantially the entire length of the cover so that the cord can be subsequently pulled out without fouling or entanglement; one end of the line *e* is secured to an elastic strap *e*¹ adapted for attachment to 45 a support, the other end being attached to the flying bridles *d*, as already stated. The two ends of the line *e* will emerge from cells at opposite edges of the cover, as seen in Fig. 5, when the 50 number of cell layers is odd, but if there are 55 two, four or other even number of layers, the

two ends will emerge from corresponding cells in upper and lower layers at the same edge of the cover, as seen in Fig. 10.

One side edge of the cover is provided with tubular members h^3 , corresponding members h^4 being provided externally near the opposite side edge; these members are so spaced to fit in between one another when the cover is rolled to closed condition, the apertures of the tubular members h^3 h^4 being then aligned to allow the insertion of fasteners i to hold the edges together, as seen more clearly in Fig. 11. These fasteners, which may consist of ordinary split pins, are tied at intervals along the other end of the line e , near its point of attachment to the flying bridles d of the kite, so that by a pull upon the line the fasteners can be withdrawn one after another to allow the unrolling of the cover. Another similar fastener i^1 , which is the last to be withdrawn by the pull of the line, serves to secure the attachment of the folded kite to a rocket j employed for its projection; an auxiliary line e^2 of suitable length, for example several feet, is provided between the wire cable j^1 of the rocket and the point of attachment upon the kite, in order to eliminate danger of the kite being ignited by the rocket during flight. The lower end of the auxiliary line is shown in Fig. 12 as being formed with an eye e^3 which is threaded through cord loops b^3 at the upper ends of the booms b , the fastener i^1 being then passed through the projecting eye e^3 so as to form a quick release device for disconnecting the rocket from the kite after the cover h has been thrown off.

As shown in Fig. 7, the kite, enclosed in its cover or container h , may be projected into the air by means of a rocket apparatus k , fired by a pistol k^1 operated by the occupier of a dinghy l , such as is employed by aircraft personnel when compelled to descend upon the sea. The rocket cable j^1 is seen to be coupled to the auxiliary line e^2 which is laid beside the roller kite-cover h , the latter being pointed in the same direction as the rocket, preferably down-wind; the elastic strop e^1 is fastened to the side of the dinghy by means of a shackle m and a fabric patch m^1 of sufficient strength to resist the pull of the line e transmitted through the strop e^1 .

Upon discharge of the pistol k^1 , the rocket j is projected into the air, carrying the kite and cover h with it at the end of the cable j^1 and auxiliary line e^2 ; when the strop e^1 is pulled tight by the rise of the rocket j and lift of the cover h , the strop begins to draw the line e out of the several cells h^2 in turn until the entire length of the line, amounting for example to more than one hundred feet for each layer of cells, has been withdrawn from the cover h . The pull is now applied to the upper end portion of the line having the fasteners i tied thereon, so that these fasteners are pulled successively out of the coupled members h^3 h^4 , leaving the cover free to unwrap from around the folded kite and to fall clear. The kite now proceeds to unfold due to the springs g drawing the spar-sections into their normal overlapping relation by causing the slides b^2 to move along the booms b , but at approximately the same moment the pull of the line e releases the last fastener i^1 from the eye e^3 so as to disconnect the rocket from the kite. The rocket then continues on its way until its energy is expended, taking the cable j^1 and auxiliary line e^2 with it, while the kite soars into the wind and exerts a strong pull through the line e and strop e^1 upon the shackle m on the dinghy; a paddle n , included in the equipment,

can be used for steering, and also for propulsion, if necessary.

It will be understood that the invention may be applied to other suitable types of kite, and that the cover or container may take various forms such as a light metal cylinder, acting for example as a projectile; the kite line need not be housed in or upon the cover enclosing the folded kite but may be drawn up from a reel or other source upon the ground, thereby enabling the flying height to be determined during the actual projection.

Any other convenient means may be provided for projecting the kite, with its cover or container, into the air; for example, there may be employed a line-throwing piston, a harpoon gun, crossbow or the like, or a compressed air gun. The small rocket apparatus above described, or a line-throwing pistol, is particularly suitable for projecting a kite to be used in raising a radio aerial or signal hoist from a ship's lifeboat, dinghy or the like, where space is restricted. Larger rocket apparatus, guns or compressed air projectors may be employed for longer lines or cables, as in the raising of a kite barrage in defense of positions vulnerable to air attack, enabling the barrage to be established quickly at a height where sufficient wind is likely to be available, even in light or variable weather conditions when there may be too little wind at ground level for the flying of kites in the customary way.

What I claim is:

1. A kite for projection to flying height, comprising a jointed frame, a sail carried by said frame, said frame and sail being adapted for folding to a compact shape, spring means connected to said frame at points thereof having relative motion in the folding of said frame, said spring means being strained by said relative motion and reacting by urging said frame to unfold for spreading said sail, means for retaining said frame and sail in folded condition against the reaction of said spring means, a kite line, and means for releasing said retaining means, said releasing means being controlled by said kite line for operation as the projected kite approaches flying height.

2. A kite for projection to flying height, comprising a jointed frame, a sail carried by said frame, said frame and sail being adapted for folding to a compact shape, spring means connected to said frame at points thereof having relative motion in the folding of said frame, said spring means being strained by said relative motion and reacting by urging said frame to unfold for spreading said sail, a cover adapted to enclose said frame and sail in folded condition, a kite-line, and means controlled by said kite-line for releasing said cover as the projected kite approaches flying height.

3. A kite for projection to flying height, comprising a jointed frame, a sail carried by said frame, said frame and sail being adapted for folding to a compact shape, spring means connected to said frame at points thereof having relative motion in the folding of said frame, said spring means being strained by said relative motion and reacting by urging said frame to unfold for spreading said sail, a cover adapted to enclose said frame and sail in folded condition, a kite-line, said cover including means for housing a substantial portion of the length of said kite line, said housing means adapted for withdrawal of said kite-line portion during projection of the kite, and means controlled by the withdrawn kite line.

for releasing said cover as the projected kite approaches flying height.

4. A kite for projection to flying height, comprising a pair of parallel booms, a sail carried by said booms, a spar normally spacing said booms apart and keeping said sail extended, said spar including two sections jointed together for folding parallel with said booms to a compact shape, springs connecting said booms to said spar sections and urging them to normal spacing relation, a cover adapted to enclose said booms, spar and sail in folded condition, a kite line, connections from said kite line to said booms, and means controlled by said kite line for releasing said cover as the projected kite approaches flying height.

5. A kite for projection to flying height, comprising a pair of parallel booms, a sail carried by said booms, a spar normally spacing said booms apart and keeping said sail extended, said spar including two sections jointed together for folding parallel with said booms to a compact shape, slides movable along said booms and guiding the adjacent ends of said spar sections, springs connecting said booms to said spar sections and urging them to normal spacing relation, a third boom, sails extending between said first mentioned booms and said third boom, a kite line connected to said third boom, a cover adapted to enclose said booms, spar and sail in folded condition, and means controlled by said kite line for releasing said cover as the projected kite approaches flying height.

6. A kite for projection to flying height, comprising a jointed frame, a sail carried by said frame, said frame and sail being adapted for folding to a compact shape, automatic means for unfolding said frame to spread said sail, a cover adapted to enclose said frame and sail in folded condition, a kite-line, said cover including a plurality of parallel pockets for housing looped portions of said kite line for successive withdrawal during projection of the kite, and means controlled by the withdrawn kite line for releasing said cover as the projected kite approaches flying height.

7. A kite for projection to flying height, comprising a jointed frame, a sail carried by said frame, said frame and sail being adapted for folding to a compact shape, spring means connected to said frame at points thereof having relative motion in the folding of said frame, said spring means being strained by said relative motion and reacting by urging said frame to unfold for spreading said sail, a cover adapted to enclose said frame and sail in folded condition, a kite-line, and fasteners normally holding said cover closed, said fasteners being attached to said kite line for automatic release of said cover as the projected kite approaches flying height.

8. A kite for projection to flying height, comprising a jointed frame, a sail carried by said frame, said frame and sail being adapted for folding to a compact shape, automatic means for unfolding said frame to spread said sail, a cover adapted to enclose said frame and sail in folded condition, a kite-line, said cover being formed of two thicknesses of fabric seamed together along parallel lines to provide a plurality of narrow pockets, looped portions of said kite line being housed in said pockets for successive withdrawal during projection of the kite, and means for retaining said cover with said looped portions housed in said pockets around said frame and sail

in folded condition, said retaining means being released by the withdrawn kite line as the projected kite approaches flying height.

9. In combination, a kite comprising a jointed frame, a sail carried by said frame, said frame and sail being adapted for folding to a compact shape, spring means connected to said frame at points thereof having relative motion in the folding of said frame, said spring means being strained by said relative motion and reacting by urging said frame to unfold for spreading said sail, a cover adapted to enclose said frame and sail in folded condition, a line attached at one end to said kite, an anchorage for the other end of said line, means controlled by said line for maintaining said cover closed, and means for projecting said cover with the enclosed frame and sail, said line operating to release said cover for the automatic unfolding of said frame at a height predetermined by the length of said line.

10. In combination, a kite comprising a jointed frame, a sail carried by said frame, said frame and sail being adapted for folding to a compact shape, spring means connected to said frame at points thereof having relative motion in the folding of said frame, said spring means being strained by said relative motion and reacting by urging said frame to unfold for spreading said sail, a cover adapted to enclose said frame and sail in folded condition, a line attached at one end to said kite, an anchorage for the other end of said line, said cover including a plurality of parallel pockets for housing looped portions of said line, disconnectible means for maintaining said cover closed, and means for projecting said cover with the enclosed frame and sail, said line portions being withdrawn from said housing pockets during the projection of said cover and operating at a height predetermined by the length of said line to release said cover for the automatic unfolding of said frame to bring the kite to flying condition.

11. A collapsible kite comprising a pair of parallel booms, a sail carried by said booms, a spar for spacing said booms apart and keeping said sail extended, said spar including two sections jointed together for folding parallel with said booms and elastic members connecting said booms to said spar sections and urging them to normal spacing relation.

12. A collapsible kite comprising a pair of parallel booms, a sail carried by said booms, a spar for spacing said booms apart and keeping said sail extended, said spar including two sections jointed together at a point intermediate their ends for folding parallel to said booms, one end of each said section being engaged in a pocket in said sail and the other end of each said section being provided with a collar slidale on one of said booms, and elastic members connecting said booms to said spar sections and urging them to normal spacing relation.

13. A collapsible kite comprising a pair of parallel booms, a sail carried by said booms, a spar for spacing said boom apart and keeping said sail extended, said spar including two sections jointed together for folding parallel with said booms, elastic members connecting said booms to said spar sections and urging them to normal spacing relation, and a removable cover adapted to retain said booms, sail and spar-sections in folded condition.

JOHN SYLVESTER WHEELWRIGHT.
